MOLDED PULP TRAY

Horace W. Raymond, Waterville, Maine, assignor to Keyes Fibre Company, Portland, Maine, a corporation of Maine

Application November 23, 1956, Serial No. 43,896

Term of patent 14 years

(Cl. D58—13)

Fig. 1 is a top plan view of a molded pulp tray embodying my new design;

Fig. 2 is a longitudinal view partly in elevation and partly in section taken on line 2—2 of Fig. 1; and

Fig. 3 is a cross-sectional view taken on line 3—3 of Fig. 1.

What is claimed:

The ornamental design for a molded pulp tray, as shown.
